UNITED STATES PATENT OFFICE

2,518,725

BLOWER ATTACHMENT FOR SEWING MACHINES

George Sauer, Berwyn, and Clarence C. Smith, Chicago, Ill., assignors to Union Special Machine Company, Chicago, Ill., a corporation of Illinois

Application December 29, 1945, Serial No. 638,186

14 Claims. (Cl. 230—243)

This invention relates to an improved combination of an electric transmitter, or individual power drive, and blower for use in connection with sewing machines. It has particular relation to a unit of this character intended for the improved operation of industrial sewing machines, as in the manner disclosed in the pending application of Harold J. LeVesconte and Albert M. Schweda, Serial No. 534,718, filed May 9, 1944, now Patent No. 2,424,102.

An object of the invention has been to provide a unit of the character indicated which has the various parts requiring adjustment readily accessible for such adjustment as well as removal and replacement. This applies particularly to the clutch operating means, brake means, and the blower.

Another object has been to provide an arrangement of and mounting means for the blower which will enable relative adjustments between the housing and rotor to be quickly and easily accomplished and which will also permit angular adjustment of the housing to any extent desired in relation to the frame of the transmitter or other support member. This allows compensation to be readily made for angular adjustment of the transmitter in tightening the belt which connects the latter with the sewing machine.

A further object has been to provide a mounting for the blower which will eliminate the necessity of relative movement between the housing and rotor members and thus permit a minimum clearance between these members, with resulting greater efficiency in the operation of the blower.

As a specific feature of the invention, simple and effective means is provided for preventing rotation relative to the frame of an axially slideable sleeve which carries the shiftable member of the clutch means of the transmitter unit.

Other objects, features, and advantages of the invention will appear from a detailed description which will now be given of several illustrative embodiments of the invention, in conjunction with the accompanying drawings in which:

Fig. 1 is a front elevational view of the improved unit, including a motor, clutch, and blower;

Fig. 2 is a view, partly in front elevation and partly in longitudinal section, through the unit shown in Fig. 1;

Fig. 3 is an end elevational view of the unit as seen from the right end of Fig. 1 but with the pulley and blower removed;

Fig. 4 is a view similar to Fig. 3 but with the blower and pulley included;

Fig. 5 is a detail view of a spider used in attaching the blower housing;

Fig. 6 is a view similar to Fig. 2 but illustrating a modified construction;

Fig. 7 is a view similar to Fig. 2 but illustrating a further modification;

Fig. 8 is a vertical sectional view taken along the line 8—8 of Fig. 7; and

Fig. 9 is a fragmentary detail view showing the form and arrangement of the clutch operating lever in the Fig. 7 construction.

Turning now to Figs. 1 to 5, there is illustrated one suitable form of the combined motor, clutch, and blower combination intended for use in driving a sewing machine of any suitable type. The improved construction may be used in the manner illustrated in the application of Charles F. Rubel, Serial No. 433,740, filed March 7, 1942, now Patent No. 2,423,996, or in the application of George Sauer, Serial No. 442,585, filed May 12, 1942, now Patent No. 2,418,429.

The improved unit has a main supporting frame designated generally by the reference character 10. This frame, in the embodiment of Figs. 1 to 5, is preferably of V-configuration in end view (Fig. 3), the V being formed by a pair of yoke members 11 and 12. Yoke member 12 is provided with a rearwardly extending ear 13, or a pair of similar ears, adapted for pivotal mounting by means of a pin, or pins, 14 upon the lower end of a downwardly extending arm or pair of arms 15 integral with, or otherwise connected with, a supporting plate 16. The latter, it will be understood, is adapted for attachment in any convenient manner, as by means of screws or the like, to the under surface of the table top which supports the sewing machine to be driven by the unit. At its forward end the supporting plate carries a pair of downwardly extending ears 17 between which there is swivelly mounted the upper end of a rod 18. This rod at its upper end is provided with a hub-like portion which fits snugly between the ears 17 and which receives a pivot pin 19 extending through the ears 17. Rod 18 is screw-threaded at its lower end and carries a pair of clamping nuts 20 adapted to embrace opposite sides of a stud 21 extending laterally from a lug 22 projecting outwardly from the member 11. Stud 21 is journalled in the lug 22 and is preferably provided with flat sides for engagement by the nuts 20. By appropriately adjusting the nuts 20 along the rod 18 the frame 10 may be angularly adjusted to a desired posi-

tion.

Fig. 2 is a view, partly in front elevation and partly in longitudinal section, through the unit shown in Fig. 1;

Fig. 3 is an end elevational view of the unit as seen from the right end of Fig. 1 but with the pulley and blower removed;

Fig. 4 is a view similar to Fig. 3 but with the blower and pulley included;

Fig. 5 is a detail view of a spider used in attaching the blower housing;

Fig. 6 is a view similar to Fig. 2 but illustrating a modified construction;

Fig. 7 is a view similar to Fig. 2 but illustrating a further modification;

Fig. 8 is a vertical sectional view taken along the line 8—8 of Fig. 7; and

Fig. 9 is a fragmentary detail view showing the form and arrangement of the clutch operating lever in the Fig. 7 construction.

tion in relation to the supporting plate 16. This, it will be understood, enables proper tightening or loosening of the belt which connects the power unit with the sewing machine.

Toward their left ends (Figs. 1 and 2) the yoke members 11 and 12 are connected with an end bell member 23 of an electric motor 24. The opposite end of the motor may be enclosed by another bell member 25 of suitable form and the entire motor casing may suitably be held together by tie rods or bolts 26. The motor may be of any suitable construction and is provided with a driving shaft 27 which extends outwardly beyond the bell 23 a suitable distance and is journaled in a bearing 28, preferably a ball-bearing, mounted within an opening in the end bell. The outer projecting end of the shaft 27 carries a flywheel 29 which is keyed to the shaft and is held firmly thereon, preferably by means of a nut 30 carried by a screw-threaded reduced portion at the end of the shaft. A washer 31 is preferably employed between the nut 30 and the end of the hub of the flywheel.

At their other or right-hand ends, Fig. 1, the yoke members 11 and 12 carry, preferably as an integral part thereof, the upper half portion 32 of a bearing retaining housing. The lower half 33 of this bearing housing may be secured to the upper half by means of screws or bolts 34, Fig. 3. Within the bearing housing there is mounted an axially slidable sleeve 35 which carries a pair of ball-bearing units 36 and 37 in enlarged openings at its opposite ends, these bearing units being arranged to support a driven shaft 38 which is axially aligned with the motor shaft 27. At its inner end the shaft 38 carries a driven clutch member 39 arranged to cooperate with a friction band 40 secured in any suitable way to the outer face of the flywheel 29. Clutch member 39 which is preferably formed with a frustro-conical outer surface arranged to cooperate with a corresponding inner surface on the friction bank 40, is secured to the shaft 38 by means of a tapered pin 41. At its outer end the shaft 38 carries a pulley wheel 42 which has splined connection with the outer end of the shaft and which is held on the latter by means of a pair of nuts 43 cooperating with a screw threaded reduced portion at the end of the shaft. The arrangement is such that the clutch member 39 at one end of the shaft 38 and the pulley 42 at the other end serves to retain the various intermediate parts, described in association with sleeve 35, as a unitary assembly. A spacing sleeve 44, surrounding the shaft 38, is provided between the bearing units 36 and 37. Rotation of the sleeve 35 within the supporting housing is prevented by a key 45 mounted within an elongated recess 46 formed by complementary key slots in the top of the sleeve and in the interior of the portion 32 of the bearing support. This key is secured by a screw 47 within the key seat in the sleeve 35. As will be seen, the arrangement is such that the sleeve 35 may be shifted axially to a limited extent with respect to the bearing support but it may not be rotated relative to such support.

The bottom portion of the sleeve 35 is formed with a plurality of rack teeth 48 which may extend for any suitable distance around the sleeve and which are adapted to cooperate with pinion teeth 49 provided in spaced relation around a rotatable stud 50. The latter is journaled within a cylindrical housing portion 51 of the member 33 and is disposed transversely of the main axis of the bearing support. At its right end (Fig. 3)

the stud 50 carries a collar 52 which is secured to the stud by a set-screw and cooperates with the adjacent end of the housing 51. At its opposite end the stud 50 carries a split collar 53 adapted to be clamped to the stud by means of a screw 54. The inner face of this split collar cooperates with the opposite end of the housing 51. It carries, preferably as an integral part, a lever arm 55 having a hole 56 at its outer end by which it is adapted to be connected, by means of a rod or chain, (not shown) with a foot treadle or other control member conveniently positioned for operation by the operator. A spring 57 connected at one end with an intermediate point on the lever 55 and at its opposite end with an eyelet 58 carried by the frame member 11 serves to rock the arm 55 in a clockwise direction (Fig. 1). This, as seen in Fig. 2, tends to shift the sleeve 35 toward the right to disengage the clutch member 39 from the friction band 40. At the same time it carries a portion of the outer face 59 of the driven clutch member against a segmental friction member 60 which constitutes a brake. This brake segment, which preferably has the configuration indicated in Fig. 3, is carried by a channel in the inner end 61 of a brake supporting slide 62. The latter is slidably mounted in a longitudinal channel 63 (Fig. 3) formed in an upward extension of the upper member 32 of the bearing housing. The slide 62 is provided with a slightly elongated slot 64 adapted to receive a clamping screw 65 which has screw-threaded engagement with the bearing housing and which serves to lock the slide in any set position on the bearing housing. For the purpose of accurate adjustment of the brake element, both initially and to compensate for wear, an adjusting screw 66 is provided. This has its shank in screw-threaded engagement with an opening 67 in the end of the slide 62 and at an intermediate point it carries a flange or collar 68 which is received by a groove 69 in the top of the upwardly projecting portion of the bearing housing 32. As will be seen, rotation of the screw 66 will thus produce longitudinal movement of the slide 62 to any extent desired. Of course the clamping screw 65 will be loosened prior to any such adjustment and will be tightened after the adjustment has been made. It will be noted, incidentally, that the cooperation of the clutch member 39 with the brake element 60 provides a limit for the rocking of the lever arm 55 by the spring 57. When the lever arm is depressed by operation of a foot treadle or the like, the stud 50 will be rotated in a counterclockwise direction and will shift the sleeve 35 toward the left (Fig. 2), thus carrying the clutch member 39 into engagement with the friction band 40 on the constantly rotating flywheel 29. At such times the sewing machine will be driven.

We come now to the blower attachment which is adapted to provide an appropriate stream of cooling air for cooling the needles or other operating devices of the sewing machine in accordance with the disclosures of the above mentioned Rubel and Sauer applications. This blower comprises a rotor having a hub portion 70 mounted on the splined portion of the shaft 38 between the inner end of the hub of pulley 42 and the outer face of the bearing 37. An impeller disc 71 is secured to the hub 70 by means of screws 72. As shown in Figs. 2 and 4, a plurality of fan or impeller blades 73, preferably of angular formation, are secured in any suitable way, as by welding or the like, to the face of the disc 71.

Surrounding the rotor there is provided a housing 14 of convolute form, as best shown in Fig. 4. This housing is preferably formed in two parts, 15 and 16, which are identical in form except for the fact that one is righthand and the other is lefthand. These parts are secured together by a series of screws 17. The housing is held in fixed relation to the frame 10 of the unit by means of a spider member 18 (Figs. 2 and 5) which has a hub portion 19 adapted to be mounted upon a cylindrical extension 20 of the upper and lower bearing housing members 22 and 23 surrounding the sleeve 35. A set screw 21 serves to hold the hub of the spider in any desired position in relation to the extension 20. This permits slight axial adjustment and infinite angular adjustment. Arms 22 of the spider are provided with holes 23 at their outer ends adapted to receive screws 24 for retaining the housing on the spider. In order that the housing may be made reversible and placed either in the position indicated in Figs. 2 and 4, or in the reverse position in which the outlet 25 is at the left rather than at the right as in Fig. 4, both sections of the housing are provided with threaded openings to receive the screws 24. Those openings which are not serving this function are closed off by means of screws 26. It will be understood that the outlet 25 of the blower is adapted to be connected by a flexible tube, or even a rigid tube, if desired, with any appropriate portion of the sewing machine for effecting the desired cooling action. By virtue of the fine angular adjustment of the housing made possible by its mounting and its retention in any desired position by the set screw 21, accurate compensation may be made for angular adjustment of the frame 10 about the pivotal support 14, for belt tightening purposes as has been explained. Thus, regardless of the angular position of the frame 10, the outlet 25 may be properly aligned with a tube carried by the supporting table, for example. So, also, the mounting of the housing provides a simple adjustment to allow for wear of the clutch faces. As these faces wear and the shaft 38, together with the rotor of the blower, is shifted further toward the left in the engagement of the clutch, the housing may be moved slightly in the same direction to avoid interference between the rotor and the housing.

Turning now to Fig. 6, a modified construction is shown in which the housing of the blower partakes of the axial movements of the rotor. Except for the mounting of the blower housing and the construction of the blower itself, the construction illustrated in Fig. 6 is identical with that illustrated in Figs. 1 to 5. Hub 79a of the spider 78a which supports the blower housing, is mounted directly upon the outer end of a shiftable sleeve 35a which corresponds with the sleeve 35 of Fig. 2. The bearing housing members 32a and 33a terminate to the left of the hub 79a. In other respects the construction is the same as in Figs. 1 to 5. However, since in the Fig. 6 arrangement the housing, as well as the rotor, will be shifted axially with the sleeve 35a and the shaft 38a, a smaller clearance may be provided between the rotor and the walls of the blower housing. A more efficient blower is thus produced. The same advantage as explained in connection with the first embodiment are provided in the way of angular and axial adjustment of the housing in relation to its support.

In Figs. 7, 8, and 9, a further modification is shown. In this construction the main supporting frame for the unit is provided with a cylind-

rical portion 87 which substantially encloses the clutch of the unit. However, to provide adequate circulation of air around the clutch parts and thus prevent overheating, the cylindrical portion of the frame is preferably provided with a series of openings 88 of suitable size. Frame member 87 is provided with a pair of ears 89 adapted to be pivotally connected, by means of a pin or bolt 90, with downwardly extending members 91 of a support 92 arranged to be secured to the under surface of the table which carries the sewing machine. A forwardly extending ear 93, provided on the cylindrical portion 87 of the housing, carries a clamping bolt 94 adapted to cooperate with an elongated slot 95 in a link 96 pivotally carried at 97 by the support member 92. This arrangement provides a very simple, but effective, means for varying the angular position of the frame for belt tightening purposes and the like. As shown in the drawings, an advantage of this modified construction is its simplicity and cheapness from a manufacturing standpoint. The parts may be largely produced as stampings.

A different style of motor is preferably employed in this modified construction. As shown in Fig. 7, what is generally known as a pump type motor 98 is employed. This has at its righthand end an enlarged head 99 provided with a flat surface 100 against which a corresponding flat face at the left end of the portion 87 of the frame may be held. A series of screws 101 may be provided for attaching the frame member 87 to the end face of the motor. The main motor shaft 102 projects beyond the end face 100 of the motor housing into the interior of the frame portion 87 where it carries a flywheel 103. This flywheel is keyed to the shaft, as shown, and is held against axial movement by one or more set screws 104. On its inner side the flywheel is provided with a series of vanes 105 adapted to induce circulation of air, a portion of which is blown into the motor housing and discharged through openings 106 in the wall of the latter. The flywheel 103, as in the previous embodiments, constitutes the driving member of the clutch, and for this purpose is provided with a frustro-conical face 107 adapted to cooperate with a corresponding internal face on a friction band 108 carried within a drum-like extension of a driven clutch member 109. The latter is secured by means of a tapered pin 110 to a driven shaft 111 which is journalled in ball-bearing units 112 and 113. These units are mounted in enlarged recesses at the opposite ends of a shiftable sleeve 114, which is slidably received within a bearing hub 115, formed as an integral part of an end closure plate 116 for the clutch housing 87. This closure plate is secured by screws 117 to the end of the clutch housing. It will be seen, therefore, that the entire driven part of the clutch, together with all of the associated devices may be mounted as a unitary assembly on the plate 116 and attached or removed from the frame whenever desired.

The means for shifting the sleeve 114 to effect engagement and disengagement of the clutch is similar to that of the first two embodiments described, but differs in detail. A small rack segment 118 is inserted in the bottom of the sleeve 114 in lieu of forming rack teeth directly in this sleeve. This rack segment moreover, operating in a key slot 119, serves also as a key to prevent rotation of the sleeve within the bearing hub. For shifting the sleeve 114 a pinion 120 is provided, this being preferably formed as an integral part of a rod or rock shaft 121 (Fig. 8). This

rock shaft is journalled within bushings 122 and 123 carried by a transversely extending bearing sleeve 124 formed integral with the bearing hub 115. The bushings 122 and 123 have an outside diameter slightly greater than the external diameter of the pinion 120 and they, in turn, fit snugly within the bore of the sleeve 124. A set screw 125 having its inner end cooperating with a groove in the rock shaft 121 serves to retain the latter against axial movement within the bushings 122 and 123. At its outer end the shaft 121 has secured thereto the hub of a lever arm 126. This is secured to the shaft by means of a set screw 127. A spring 128 coiled about the shaft 121 and having one end bent over the end of the bearing sleeve 124 and its other end bent over the arm 126, serves to urge the latter in a clockwise direction (Fig. 9) and thus serves to urge the sleeve 114 toward the right (Fig. 7) to disengage the clutch. The extent of movement of the arm, sleeve, and clutch is determined by the position of a brake element 129, similar to brake element 60 and mounted in substantially the same manner in a slide 130 which may be adjusted by a micrometer screw 131 and retained in any set position by a screw 132. The end plate 116 of the clutch housing is provided with an opening 133, of arcuate form as shown in Fig. 8, to permit the free passage therethrough of the brake and its support in the assembly and adjustment of the parts. It will be understood that the arm 126 is adapted for connection, by a rod or chain, with a foot treadle or other control member so that the clutch may be engaged against the action of the spring 128 at the will of the operator.

At the outer end of the shaft 111 there is mounted a pulley wheel 134 in the same manner as the pulley wheel 42 in Fig. 2. Between this pulley wheel and the end of the bearing hub 115 there is mounted a blower including a rotor 135 and a housing 136. These may suitably be of the same construction as the corresponding parts illustrated in Fig. 2. The housing may, as shown, be mounted upon a cylindrical portion of the hub 115 by means of a spider 137. However, if desired, the arrangement may be similar to that shown in Fig. 6 so that the spider is mounted upon the sleeve 114 rather than an extension of the hub 115.

While several illustrative embodiments of the invention have been disclosed in considerable detail, it will be understood that numerous variations may be made in the construction and arrangement of the several parts without departing from the general principles and scope of the invention.

We claim:

1. A sewing machine power unit which comprises a support, a motor carried by said support and provided with a drive shaft, a clutch having a driving member secured to said drive shaft, said clutch having a driven member including an axially slidable shaft carried by said support, power transmitting means secured to said slidable shaft, a blower having a rotor secured to said axially slidable shaft and a housing surrounding said rotor, and readily accessible screw means for retaining said housing on said support, said screw means being arranged upon simple loosening and retightening to enable angular adjustment and resetting of said housing to any desired angular position about said slidable shaft.

2. A sewing machine power unit which comprises a support, a motor carried by said support and provided with a drive shaft, a clutch having

a driving member secured to said drive shaft, said clutch having a driven member including an axially slidable shaft carried by said support, power transmitting means secured to said slidable shaft, a blower having a rotor secured to said axially slidable shaft and a housing surrounding said rotor, and readily accessible screw means for retaining said housing on said support, said screw means being arranged upon simple loosening and retightening to enable angular adjustment and resetting of said housing to any desired angular position about said slidable shaft, said screw means being adapted to enable axial adjustment of said housing in relation to said rotor.

3. A sewing machine power unit which comprises a support, a motor carried by said support and provided with a drive shaft, a clutch having a driving member secured to said drive shaft, said clutch having a driven member including an axially slidable shaft carried by said support, a blower having a rotor secured to said axially slidable shaft and a housing surrounding said rotor, and means for retaining said housing on said support in any desired angular position about said slidable shaft, said retaining means including a sleeve concentric with said slidable shaft and carried by said support and a hub connected with said housing adapted for angular adjustment on said sleeve.

4. A sewing machine power unit which comprises a support, a motor carried by said support and provided with a drive shaft, a clutch having a driving member secured to said drive shaft, said clutch having a driven member including an axially slidable shaft carried by said support, a blower having a rotor secured to said axially slidable shaft and a housing surrounding said rotor, and means for retaining said housing on said support in any desired angular position about said slidable shaft, said retaining means including a member shiftable with said slidable shaft and means connecting said member with said housing for joint movement thereof.

5. A sewing machine power unit which comprises a support, a motor carried by said support and provided with a drive shaft, a clutch having a driving member secured to said drive shaft, said clutch having a driven member including an axially slidable shaft carried by said support, a blower having a rotor secured to said axially slidable shaft and a housing surrounding said rotor, and means for retaining said housing on said support in any desired angular position about said slidable shaft, said retaining means including a sleeve surrounding said slidable shaft and shiftable therewith and a hub connected with said housing mounted on said sleeve.

6. A sewing machine power unit which comprises a support, a motor carried by said support and provided with a drive shaft, a clutch having a driving member secured to said drive shaft, said clutch having a driven member including an axially slidable shaft carried by said support, a blower having a rotor secured to said axially slidable shaft and a housing surrounding said rotor, and means for retaining said housing on said support comprising a sleeve carried by said support and a hub mounted on said sleeve and connected with said housing.

7. A sewing machine power unit which comprises a support, a motor carried by said support and provided with a drive shaft, a clutch having a driving member secured to said drive shaft, said clutch having a driven member including an axially slidable shaft carried by said support, a

blower having a rotor secured to said axially slideable shaft and a housing surrounding said rotor, and means for retaining said housing on said support comprising a sleeve carried by said support, a hub mounted on said sleeve and connected with said housing, and means for securing said hub to said sleeve in desired angular and axial relation.

8. A sewing machine power unit which comprises a support, a motor carried by said support and provided with a drive shaft, a clutch having a driving member secured to said drive shaft, said clutch having a driven member including an axially slideable shaft carried by said support, a blower having a rotor secured to said axially slideable shaft and a housing surrounding said rotor, and means for retaining said housing on said support comprising a member rigidly connected with said housing and shiftable axially with said slideable shaft but held against rotation therewith.

9. A sewing machine power unit which comprises a member adapted for attachment to a table, a motor and clutch unit having a frame pivotally connected with said member and adjustable in relation thereto for belt tightening purposes, said unit including an axially shiftable driven shaft, a blower having a rotor secured to said shaft and a housing surrounding said rotor, said housing having a discharge outlet at one side thereof, and means for mounting said housing on said frame, said means comprising a single screw member enabling infinite angular adjustment of said housing to compensate for belt-tightening adjustment of said frame.

10. A sewing machine power unit which comprises a member adapted for attachment to a table, a motor and clutch unit having a frame pivotally connected with said member and adjustable in relation thereto for belt tightening purposes, said unit including an axially shiftable driven shaft having a belt pulley at its outer end, a blower having a rotor secured to said shaft adjacent the inner side of said pulley and a housing surrounding said rotor, said housing having a discharge outlet at one side thereof, and means for mounting said housing on said frame, said means enabling angular adjustment of said housing to compensate for belt-tightening adjustment of said frame and axial adjustment of said housing relative to said pulley.

11. A sewing machine power unit which comprises a member adapted for attachment to a table, a motor and clutch unit having a frame pivotally connected with said member and adjustable in relation thereto for belt tightening purposes, said unit including an axially shiftable driven shaft, a blower having a rotor secured to said shaft and a housing surrounding said rotor, said housing having a discharge outlet at one side thereof, and means for mounting said housing on said frame, said means including a spider connected with said housing and having a hub mounted upon a cylindrical surface formed on a member carried by said frame and including screw means cooperating with said cylindrical surface and enabling angular adjustment of said spider thereon.

12. A sewing machine power unit which comprises a support, a motor carried by said support and provided with a drive shaft, a clutch having a driving member secured to said drive shaft, said clutch having a driven member including an axially slideable shaft, a shiftable sleeve carrying said slideable shaft and shiftable therewith on a portion of said support to engage and disengage the clutch, means for preventing rotation of said sleeve, and a blower having a rotor mounted on said slideable shaft and a housing mounted on said sleeve.

13. A sewing machine power unit which comprises a support, a motor carried by said support and provided with a drive shaft, a clutch having a driving member secured to said drive shaft, said clutch having a driven member including an axially slideable shaft, a shiftable sleeve carrying said slideable shaft and shiftable therewith on a portion of said support to engage and disengage the clutch, means for preventing rotation of said sleeve, and a blower having a rotor mounted on said slideable shaft and a housing mounted on said sleeve, a portion of said support being readily detachable from the remainder thereof and enabling removal of said sleeve, slideable shaft and blower as a unit.

14. A sewing machine power unit which comprises a support, a motor carried by said support and provided with a drive shaft, a clutch having a driving member secured to said drive shaft, said clutch having a driven member including an axially slideable shaft carried by said support, a blower having a rotor secured to said axially slideable shaft and a housing surrounding said rotor, means for retaining said housing on said support in any desired angular position about said slideable shaft, said retaining means including a sleeve concentric with said slideable shaft and carried by said support and a hub connected with said housing adapted for angular adjustment on said sleeve, a brake member positioned between said driven member of the clutch and said housing for engagement by said driven member as the latter is disengaged from said driving member, and means for adjusting said brake in a direction parallel with said slideable shaft.

GEORGE SAUER.
CLARENCE C. SMITH.
